(57) **CLAIM**

I claim the ornamental design for a head light, as shown and described.

DESCRIPTION

FIG. 1 is a perspective view of a head light, shown in an environment of use;

FIG. 2 is a front elevation of the head light of FIG. 1;

FIG. 3 is a rear elevation of the head light of FIG. 1;

FIG. 4 is a left side elevation of the head light of FIG. 1;

FIG. 5 is a right side elevation of the head light of FIG. 1;

FIG. 6 is a top view of the head light of FIG. 1; and,

FIG. 7 is a bottom view of the head light of FIG. 1.

The broken lines in the drawings depict portions of the head light that form no part thereof.

1 Claim, 6 Drawing Sheets
